(57) **CLAIM**

The ornamental design for a light emitting diode, as shown.

DESCRIPTION

FIG. 1 is a perspective view of a first embodiment of a light emitting diode in accordance with the present design, as viewed from above;

FIG. 2 is a perspective view thereof as viewed from below; FIG. 3 is a front elevational view thereof. A rear elevational view would be identical to FIG. 3;

FIG. 4 is a top plan view thereof;

FIG. 5 is a bottom plan view thereof;

FIG. 6 is a right side elevational view thereof. A left side elevational view would be identical to FIG. 6;

FIG. 7 is a perspective view of a second embodiment of a light emitting diode in accordance with the present design, as viewed from above;

FIG. 8 is a perspective view thereof as viewed from below; FIG. 9 is a front elevational view thereof. A rear elevational view would be identical to FIG. 9;

FIG. 10 is a top plan view thereof;

FIG. 11 is a bottom plan view thereof; and,

FIG. 12 is a right side elevational view thereof. A left side elevational view would be identical to FIG. 12.
